UNITED STATES PATENT OFFICE.

JEAN KESSLER, OF FRANKFORT-ON-THE-MAIN, GERMANY.

LOCK.

No. 868,867.

Specification of Letters Patent.

Patented Oct. 22, 1907.

Application filed January 2, 1906. Serial No. 294,287.

To all whom it may concern:

Be it known that I, JEAN KESSLER, a subject of the Emperor of Germany, and a resident of Frankfort-on-the-Main, Germany, have invented a certain new and useful Improvement in Locks, of which the following is a specification.

This invention relates to a lock of the type wherein a box-shaped locking bolt is secured by a tumbler and the invention consists in arranging the lock so that it can be applied to doors formed with beadings and more especially to folding doors. For this purpose the keeper is not screwed to one leaf of the door or to the door jamb but is removably mounted and is formed with a tongue, which in combination with a holder forms the part of the lock into which the locking bolt is shot. The plate carrying the locking bolt is mounted on one leaf of the door and the holder on the other leaf or on the door jamb.

In the accompanying drawing which illustrates the invention Figure 1 shows the improved lock in locked position with part of the locking bolt broken away. Fig. 2 is a section on the line A—B of Fig. 1.

As shown, on one leaf *f* of a door is screwed a plate *p* in which is guided the locking bolt *g*. Between the plate *p* and said bolt is the tumbler *s* which engages a lug *a* on the plate *p* and secures the bolt *g* in locked position when the bolt *g* has entered the casing or keeper *k*. On the other leaf of the door or on the door jamb is attached a holder *h* of U-form which is closed on its lower side and arranged at the same height as and exactly opposite the locking bolt. Between the latter and the holder which is separated therefrom by the molding or beading *l* on the door leaf *f* may be inserted the keeper *k* provided with a projection carrying a tongue *z* the profile of which corresponds to that of the beading *l*.

The method of securing the lock is as follows: On the movable leaf *f* is screwed the plate *p* and the locking bolt *g* is moved towards the right over the same. Thereupon the keeper *k* with the tongue *z* is slid vertically along the beading *l* until the said tongue abuts against the foot of the holder *h*. Now on moving the bolt *g* towards the right the same enters a recess in the keeper *k* and when the tumbler *s* has by means of a suitable key been brought over the lug *a* on the plate *p* the door will be securely locked against opening. The bolt *g* is so formed that the fastening screws for the plate *p* are covered over, and the tongue *z* is designed to conceal the fastening screws on the holder *h*. So as to have the fastenings of the holder readily accessible the upper limb of the same is provided with suitable notches *m*. Since with the lock closed the fastenings are inaccessible the lock can only be burst open by force or by an authorized person provided with a key. The lock may thus be regarded as a safety lock.

Having now described my invention what I claim and desire to secure Letters Patent of the United States is:—

The improved door-lock, comprising in combination, a locking-bolt carried on one part of the door, a tumbler for securing said locking bolt, a holder attached to the other part of the door, and a movable keeper adapted to engage the locking-bolt and having a tongue portion adapted to be slid into the holder and to cover the lock fastenings, as and for the purpose set forth.

In testimony whereof I have signed my name to this specification in the presence of two subscribing witnesses.

JEAN KESSLER.
